UNITED STATES PATENT OFFICE.

WILLIAM C. COLEMAN, OF WICHITA, KANSAS.

CENTRIFUGAL SEPARATOR AND AMALGAMATOR.

Application filed September 6, 1924. Serial No. 736,374.

This invention relates to a centrifugal separator and amalgamator for centrifuging ore sludge or pulp.

The invention contemplates a centrifugal machine designed so that the ore pulp may pass through it at a relatively slow rate to allow the mercury to act upon the pulp to absorb or separate the precious metals from the pulp and means is provided so that outlet from the mercury space and preferably the inlet as well, will be restricted so that the rate of flow of the material through the mercury space or chamber will be slow enough to insure a relatively high yield of precious metal.

I have found that where the material passes through the machine too rapidly, the mercury does not have a chance to extract all of the precious metal. In such cases the yield is very much lower than where the passage through the mercury chamber is retarded. In other words there is a time element to be taken into consideration with respect to the passage of the pulp over the mercury.

I have also found that where the mercury is relatively still within the rotor of the centrifugal separator that the centrifugal force appears to compact the mercury against the wall of the rotor to such an extent that the surface tension of the mercury is so great that the fine particles of precious metal cannot penetrate the surface of the mercury. In that case, the yield is cut down to what is possible after the surface is broken up so I have provided means in the present construction which causes the mercury to be continuously more or less in a state of agitation so as to reduce the surface tension and to this end I provide agitating means for the mercury.

The invention further contemplates an outer rotor and an inner rotor in inverted relation and spaced apart, preferably rotating together, the outer rotor being provided with a central outlet opening, the wall of the inner rotor being in spaced relation between two walls of the outer rotor and in actual practice, I have found that when the pulp passes from the outer space between the outer wall of the outer rotor and the wall of the inner rotor to the inner space between the wall of the inner rotor and the inner wall of the outer rotor that the cen-

trifugal force tends to cause the pulp to whirl and the whirling motion seems to cause it to stratify horizontally so that it forms an opposing screen to the incoming pulp from the outer space to the inner space. In order to break down the wall formed by the whirling centrifugal actuated pulp, it becomes necessary to use considerable power to force the material into the machine, but by providing deflecting vanes or blades on the inner wall of the outer rotor within the inner space, I am enabled to break up this whirling motion and cause an easy flow of the refuse pulp through the inner space toward the discharge opening of the machine.

I am also enabled by the construction herein described to practically eliminate the mercury from being carried over with the refuse to the discharge opening of the machine, this being accomplished by the peculiar construction of the wall of the outer rotor as will be apparent after the nature of the invention is better understood.

The main features of my invention will be clearly appreciated by reference to the following description in connection with the accompanying drawings, in which—

Fig. 1 is a vertical longitudinal sectional view through a centrifugal separator and amalgamator constructed in accordance with my invention.

Fig. 2 is a sectional fragmentary view through the outer part of the outer wall of the outer rotor showing one form of mercury agitator, and

Fig. 3 is a like view showing another form of mercury agitator.

Referring now to the drawings by numerals of reference—

1 designates a head which may be suitably supported for example on the beams 2 and 3. The head is provided with a vertical bearing 4 having a hollow shaft 5 and there is a thrust bearing 6 which may be of appropriate construction. The hollow shaft 5 is driven by suitable power applied to a pulley 7 or other appropriate power transmitting means.

The upper end of the hollow shaft 5 may be in communication with a suitable conduit through which by means of a pump, pulp is supplied to the shaft 5, the shaft 5 serving both as a drive shaft and as a pulp

conducting conduit. On the lower end of the shaft 5 is fastened a cover 8 constituting part of an outer rotor.

The outer rotor has an outer wall 9 and 5 an inner wall 10, the two walls being in spaced relation and connected at their bottom edges by a constricted portion 11, the outer wall 12 of which is inclined upwardly and outwardly toward the offset mercury 10 space or chamber 13 in the wall 9.

The inner wall 10 merges into a conical member 14 surrounding a discharge port opening 15. The conical portion carries deflector wings or blades 16 spaced apart 15 around the axis of the outer rotor. The outer rotor as will be apparent from the above description is cup shaped with a double wall to provide a suitable space for the wall of the inner rotor and for the 20 mercury chamber. The inner rotor is inverted with respect to the outer rotor, that is its horizontal wall 17 is at the upper portion of the machine and it is in the form of a disk which overlaps the vertical wall 17' 25 slightly providing a flange 18 which constricts the space 19 communicating the sludge space 20 with the amalgamator chamber 13.

The depending wall 17' of the inner rotor 30 extends to a point nearly to the bottom of the portion 11 so that the space 21 between the lower edge of the wall 17 and the wall of the outer rotor is constricted with respect to the amalgamator chamber for a purpose 35 which will be presently explained.

The disk 17 is held in spaced relation with the cover to provide the chamber 20 by separators 22 through which the bolts 23 for fastening the two rotors together 40 pass. The cover and outer rotor wall 9 are fastened together by the bolts 24.

Within the mercury chamber is an agitator consisting of a corrugated sheet 25 suitably fastened to the outer wall of the 45 outer rotor. This sheet may be in the form of an amalgamator blade if desired, or I may corrugate the inner surface of the outer wall 9 of the rotor as indicated at 26 (Fig. 3), or if desired other agitating 50 means may be provided for the mercury, the important feature being that the mercury be broken up or be caused to agitate so that the surface tension will be destroyed.

When the parts are assembled, the pulp 55 will be fed into the machine through the conduit or hollow shaft 5 which may all the while be rotated by power applied to the pulley 7 fast on the shaft. After the material is fed upon the disk or table 17, it will 60 be distributed by centrifugal force off the edges of the disk into the amalgamator space between the wall of the inner rotor and the outer wall of the outer rotor. After the pulp reaches the amalgamator or separator chamber, the centrifugal force of the

machine will tend to separate out the larger particles of precious metal, the fine particles being absorbed by the mercury and since the mercury will be in a state of agitation, due to the fact that it tends to lag so that the 70 corrugations ride over it, the resistance of the mercury will be less and the penetrability of the precious metal will be greater than could be possible where the surface tension was maintained to any considerable extent. 75

I have shown corrugations for causing agitation, but I do not wish to be limited to any particular form of agitator, the important feature being that the surface tension of the mercury be reduced to a minimum. 80

After the pulp passes through the amalgamator and separator chamber, it will gravitate to the bottom of the outer rotor to the constricted portion 11 where its flow 85 will be retarded so that it will not pass too rapidly into the inner space between the wall 10 and the wall 17'. Therefore the pulp will remain in the separator chamber long enough to be thoroughly acted upon by 90 the centrifugal machine and the mercury so that practically all of the precious metal will be taken out of the pulp. The metallic impoverished pulp, now refuse will pass into the inner chamber where it will contact with the blades 16 and since the blades 16 will resist any tendency for the pulp to slip with relation to the rotor, the pulp can readily pass out through the orifice 15. 95

The blades or vanes are quite important, 100 for without them, the pulp would form in a whirling mass tending to scour against the greatest diameter of the inside chamber or space and stratify horizontally so as to oppose the passage of the pulp from the outer chamber to the inner chamber. As a result sufficient power would have to be exerted on the incoming pulp to break down the horizontal strata but by providing the blades or vanes 16 the material cannot 105 stratify. 110

It is characteristic of centrifugal separators that the machine travels faster than the pulp so there is more or less scour on the mercury but the mercury will tend to move toward the greatest diameter of the outer rotor so by providing the outwardly and upwardly inclined wall 12 an easy angle is provided up which the mercury may ride into the mercury space, so that liability of the 115 mercury being carried over with the refuse and out through the outlet 15 will be eliminated. 120

The device can be readily assembled by first connecting the inner rotor to the cover, 125 introducing the mercury in the bottom of the outer rotor and fastening the outer rotor and cover together. The cover of course may be secured in an appropriate manner to the shaft or hollow conduit 5. 130

I have not shown the pump for pumping the pulp into the hollow shaft or conduit 5 as this is old construction and any suitable means may be provided for introducing the material into the machine.

What I claim and desire to secure by Letters-Patent is:—

1. A centrifugal separator and amalgamator comprising an outer rotor having an inlet and an outlet, the rotor having a mercury chamber, an inner rotor in spaced relation with the first to divide the first named rotor into two communicating chambers, the two chambers communicating through a vertically constricted passageway at the lowermost part of the outer rotor so as to retard the flow of material through the mercury chamber, the outlet for the outer rotor being within the inner rotor and vanes 20 about the outlet.

2. A centrifugal separator and amalgamator comprising an outer rotor and an inner rotor, the outer rotor comprising an inlet having a casing at its top and an outlet at its bottom, and provided with a mercury chamber, the inner rotor comprising an inverted cup shaped member in spaced relation with the outer rotor and immediately beneath the inlet so that the inner rotor constitutes a distributor for delivering the material into the mercury chamber, the free edge of the inner rotor being closer to the wall of the outer rotor than any other part of the inner rotor and means for rotating 35 the rotors.

3. A centrifugal separator and amalgamator comprising an outer rotor consisting of an enclosing casing provided with an inlet at its top and an outlet at its bottom, the outer rotor having a mercury chamber at its greatest diameter, the lower portion of the wall of the outer rotor being in the form of a groove having a wall inclined outwardly toward the mercury chamber, an inverted cup 45 shaped member secured within the outer rotor in spaced relation thereto, having a free edge in the groove shaped portion of the bottom of the casing closer to the outer rotor than any other part of the inner rotor to provide a restricted space communicating the space outside the cup shaped member with a space inside the cup shaped member and a corrugated agitating means in the mercury chamber.

4. A centrifugal separator and amalgamator comprising an outer rotor consisting of an enclosing casing provided with an inlet at its top and an outlet at its bottom, the outer rotor having a mercury chamber at its greatest diameter, the lower portion of the wall of the outer rotor being in the form of a groove having a wall inclined outwardly toward the mercury chamber, an inverted cup shaped member secured within the outer rotor in spaced relation thereto, having a

free edge in the groove shaped portion of the bottom of the casing closer to the outer rotor than any other part of the inner rotor to provide a restricted space communicating the space outside the cup shaped member 70 with a space inside the cup shaped member, agitating means in the mercury chamber and stream line deflecting members within the space bounded by the cup shaped member.

5. A centrifugal separator and amalgamator comprising an outer rotor having a double wall at its lower end and a mercury space in its outer wall, the inner wall having on outlet, a feed tube connected to the outer rotor, the two walls of the outer rotor being connected by a portion having a wall inclined upwardly toward the mercury space and an inverted cup shaped rotor within the outer rotor in spaced relation, the free edge of the inner rotor being received in the bottom portion of the space formed by the member which connects the two walls of the outer rotor, the free edge of the inner rotor being closer to the outer rotor than any other part of the inner rotor.

6. A centrifugal separator and amalgamator comprising an outer rotor and an inner rotor in spaced relation, the outer rotor having a double wall to provide a space for the wall of the inner rotor, the inner wall of the space of the outer rotor extending from the bottom terminating short of the top and surrounding an outlet opening in the outer rotor, there being a mercury space in the outer wall of the outer rotor, the inner rotor 100 having a wall extending toward the bottom and spaced from the outer rotor, the space at the bottom of the outer rotor being constricted with respect to the distance between the walls of the outer and inner rotors, deflector 105 blades on the inner wall of the outer rotor and means for feeding material into the space between the two rotors.

7. A centrifugal separator and amalgamator comprising an outer rotor and an inner 110 rotor travelling at the same speed and in spaced relation, the outer rotor having a double wall to provide a space for the wall of the inner rotor, the inner wall of the space of the outer rotor extending from the bottom terminating short of the top and surrounding an outlet opening in the outer rotor, there being a mercury space in the outer wall of the outer rotor, the inner rotor having a wall extending toward the bottom 115 and spaced from the outer rotor, the space at the bottom of the outer rotor being constricted with respect to the distance between the walls of the outer and inner rotors, deflector blades on the inner wall of the outer 120 rotor and means for feeding material into the space between the two rotors.

In testimony whereof I affix my signature.

WILLIAM C. COLEMAN.
